CENTRALIZED TRAFFIC CONTROLLING SYSTEM FOR RAILROADS

Filed Feb. 14, 1934

UNITED STATES PATENT OFFICE

2,082,180

CENTRALIZED TRAFFIC CONTROLLING
SYSTEM FOR RAILROADS

Winfred T. Powell, Rochester, N. Y., assignor to
General Railway Signal Company, Rochester,
N. Y.

Application February 14, 1934, Serial No. 711,175

23 Claims. (Cl. 246—3)

This invention relates to centralized traffic controlling systems for governing traffic on railroads and more particularly to the interrelation of the communication part of such a system with the traffic controlling devices which are supervised thereby.

In a centralized traffic controlling system of the type contemplated by this invention, communication is established between a central control office and a large number of outlying field stations by means of a station selective coded type of communication system. In a communication system of this type a plurality of series of impulses of different code combinations are transmitted over the line circuit connecting the control office and the field stations. The first part of each different series of code combinations is employed for the selection of the station. The later part of each different series of code combinations is employed to control the traffic controlling devices at the selected station.

The present invention pertains more particularly to the manner in which the later part of each different series of code combinations functions to control the controlling devices at the station. More specifically a track switch is governed in accordance with the conditions of switch control relays. Similarly the signals are governed by signal control relays which establish the direction, but the particular route over the track switch for such direction is dependent upon a selection which requires that the signal and switch control relays are in correspondence.

These switch and signal control relays receive their selective energizations in accordance with the distinctive character of the impulses comprising the later part of each series of code combinations. The switch and signal control relays are of the neutral type, one for positioning the switch machine to normal, one for positioning the switch machine to reverse, one for clearing signals for east bound traffic (right direction), one for clearing signals for west bound traffic (left direction) and two for putting all signals to stop.

An important feature of the present invention relates to the impulse check arrangement, whereby the recording or the reception of an extra impulse due to a surge or the like on the line at any step of the later part of a series, or the failure to record an impulse at any of these steps cancels or annuls the record for that cycle. This results in the traffic controlling devices remaining in their former positions instead of being changed

to undesired positions due to an improper code being received.

More specifically the code (+) (+) (—) is used to actuate the track switch to normal and to clear the signal for east bound traffic. If the first impulse is not recorded or if both a (+) and a (—) is recorded on the first step the switch machine is not operated and the signal is not cleared. If the second impulse is not recorded then the third impulse serves as a check, that is, if it is (—) the east bound signal is cleared but if it is 0 (no impulse) then no signal is cleared. If the first two impulses are properly received (+) (+) and a (+) and a (—) are recorded on the third step, or if no impulse is recorded on the third step no signal is cleared. If the character of the second impulse changes from (+) to (—) or the third changes from (—) to (+) the code plan is such that the signals will all be put to stop rather than a wrong signal being cleared. This same check scheme is effective for other combinations as will be pointed out in detail later.

Other features of the present invention reside in the various circuit arrangements which are particularly adaptable for systems of this type.

In describing the invention in detail reference will be made to the accompanying drawing in which the various parts are designated by suitable reference characters. This drawing illustrates diagrammatically the apparatus and circuits provided in accordance with the present invention at a typical field station for the control of a single track switch and the signals for governing traffic thereover.

For the purpose of simplifying the illustration and facilitating in the explanation, the various parts and circuits constituting the embodiment of the invention have been shown diagrammatically and certain conventional illustrations have been employed. The drawing has been made more with the purpose of making it easier to understand the principles and mode of operation, rather than with the idea of illustrating the specific construction and arrangement of parts that would be employed in practice. For example, the various relays and the contacts are illustrated in a conventional manner with symbols employed to indicate the connections to the terminals of batteries or other source of direct current instead of showing all the wiring connections to these terminals. The symbols (+) and (—) are employed to indicate the positive and negative terminals respectively of suitable batteries or other sources of direct current and

the circuits with which these symbols are used always have current flowing in the same direction.

Communication system in general.—A centralized traffic controlling system in which the present invention is more particularly useful consists of a control office and a number of outlying field stations. Communication is established between the control office and the field stations for the transmission of controls for governing the traffic controlling devices at such stations and for the transmission of indications to give the operator in the control office information as to the location of trains and the response of the various traffic controlling devices. This communication is established over a station selective coded type communication system, in which a small number of line conductors is employed and in which the selective communication between the office and any particular station, either for the transmission of controls and/or the transmission of indications, is established by the transmission of suitable codes.

For the purpose of illustrating the present invention it is considered unnecessary to illustrate the apparatus in the control office for applying a plurality of a series of different code combinations to the line circuit in accordance with the positions of code jumpers and control levers and it is also considered unnecessary to illustrate the reception of code combinations transmitted from the field stations to the control office. It is assumed that a system for these purposes may be of any suitable character such for example as shown in the application of T. J. Judge, et al., Ser. No. 640,062, filed October 28, 1932, corresponding to British Patent 419,399.

It is considered sufficient for an understanding of the present invention to merely illustrate how the control code part of each series of impulses results in the control of the traffic governing devices at a particular station and to indicate the relation of the apparatus shown with the rest of the apparatus of a complete system.

With reference to the accompanying drawing a control office has been merely indicated by a dotted rectangle. The control office is connected to the field station by three line wires, including a control line 10, an indication line 12 and a common return line 14, it being understood that these lines extend from the office to each of the field stations of the system. The line wires 10 and 12, together with the common return line wire 14 are so employed as to complete two line circuits namely, a control line circuit and an indication line circuit. The control line circuit is for the transmission of impulses of selected polarity from the control office to the field stations and includes at each field station a three position, polar, biased-to-neutral, line relay F.

The transmission of a series of distinctive impulses over the control line circuit results in the step-by-step operation of a stepping relay bank at each station, irrespective of the character of impulses, while the character of the impulses determine the particular field station to be selected. A station relay ST at each station is energized after the reception of the station selecting portion of the code combination which corresponds to the station at which this station relay is located. Relay ST corresponds to and may be considered as being operated in the same manner as station relay SO¹ of the above mentioned Judge et al. application.

At the particular station where the relay ST

is selected, the remaining impulses of the cycle are effective to establish the proper control conditions. At those stations where the ST relays are not energized at the end of the station selecting portion of the cycle, the remaining impulses of the cycle are ineffective to establish control conditions.

For the transmission of indications to the control office, only one field station is rendered effective to transmit over the indication line circuit during any particular cycle. That particular station which is rendered effective, is selected by means of some suitable lockout arrangement. In any event, this selection of a field station for permitting it to transmit indications is made effective at such station by the continued energization of its selecting or lockout relay throughout the cycle of operations, but since this particular portion of the system is immaterial for an understanding of the present invention the circuit arrangements relating to the transmission of indications are omitted.

Field station apparatus.—The field station includes, besides the line relay F above mentioned, a neutral line repeating relay FP of the quick acting type, which is energized each time line relay F is energized, irrespective of the polarity of energization of relay F.

A slow acting neutral relay SA is picked up at the beginning of each cycle and is dropped at the end of each cycle, although it is energized only during the successive energizations of the control line circuit as repeated by relay FP. This is because relay SA has the proper slow acting characteristics.

In addition to the station relay ST above mentioned, a station stick relay STS is provided for checking the condition of the control apparatus at the start of a cycle, that is, if the control relays are all in their normal, de-energized positions at the start of the cycle relay STS will be picked up to connect these control relays to the control buses for receiving the coded impulses. If one or more of the control relays is picked up at the start of a particular cycle then relay STS cannot be picked up, with the result that no control code except the stop code can be received during this cycle.

The field station includes a stepping relay bank which takes one step for each de-energized condition of the control line. Although the stepping relays have been indicated as being picked up during the de-energized periods of the control circuit, so that the energized condition of the control line circuit may be directly executed or stored on each step, it is understood that these operations can be reversed if desired.

A slow acting last step relay LV is indicated as being operated in conjunction with the other stepping relays of the bank, this relay being picked up on the last step of the cycle. Due to its slow acting characteristics it is not dropped at the end of the cycle until a period of time has been measured off after the other stepping relays have been de-energized.

Although the field station is illustrated as including but a single track switch TS it will be understood that any number of track switches may be similarly controlled at a field station. Track switch TS is operated from one extreme locked position to the other by a suitable switch machine SM which may be of any suitable type known to those skilled in the art.

Associated with the track switch and the switch machine, a switch box or point detector

contacts (not shown) are provided for controlling a switch position repeating relay. This switch repeating relay is not shown but it may be of the polar neutral type for repeating the position and the locked or unlocked condition of the track switch in a manner familiar to those skilled in the art.

Suitable signals 1A—1B and 2A—2B are provided for governing traffic over the track switch according to the usual practice. Although these signals have been illustrated as of the color light type, they may be of any other suitable type governed in accordance with the present invention. These signals are normally at stop but are cleared whenever their corresponding signal control relays (not shown) are energized, subject to the usual automatic block protection. Such control has been indicated in the drawing by conductors RW, NW, RE and NE leading to the bracket which indicates that these conductors are connected to signal control relays for clearing signals 2B, 2A, 1B and 1A respectively. It will be understood that these signal clearing circuits are governed in accordance with the position of the switch repeating relay and also in accordance with traffic conditions in advance, all of which need not be shown for a proper understanding of the present invention.

The track switch TS also has associated therewith the usual detector track section, having the usual track battery and track relay T. A slow acting relay TP is provided for directly repeating the track relay T for purposes that will be later pointed out.

For the purpose of controlling the operation of switch machine SM, two switch machine control relays WN and WR of the neutral type have been provided. With relay WN energized and relay WR de-energized the circuits are so arranged that the switch machine will be operated to its normal locked position. With relay WR energized and relay WN de-energized the switch machine will be operated to its reverse locked position. With these relays both energized or both de-energized the circuits are so arranged that the switch machine circuits are not energized for operating the switch machine in any manner.

The direction of traffic over the track switch is determined by the direction control relays LD and RD, only one of which may remain up at any one time for controlling the signals. The particular route for the direction selected by these relays is determined by the position of the switch control relays WN and WR and as above mentioned in correspondence with the switch repeating relay (not shown).

Various other apparatus and devices for the field station includes a change relay, indication determining contacts and the like, all of which have been omitted for the purpose of simplifying the present disclosure.

It is believed that further characteristic functions and features of the invention will be best understood by considering various typical operations of the present embodiment.

Operation

As above mentioned the first part of each different series of impulses forms a combination that may be termed a station code call for the selection of a particular station, while the later part of each different series forms a combination for controlling the various devices at the selected station. Consideration of the station code calls will be given only general mention,

while detailed consideration will be given the later or control code part of each different series of impulses.

With the possibility of having either a positive or a negative impulse for each step the number of possible code combinations is equal to two raised to the power of the number of steps. In the present illustration the first two steps have been employed for the station selection part of the code. The next three steps (3, 4, and 5) have been employed for the control codes and with the impulses for these three steps arranged in code combinations, eight different codes may be formed as illustrated in the table given below.

Table of control codes

Code no.	First step	Second step	Third step	Code use
1-----	+	+	+	Switch normal, signals stop.
2-----	+	+	-	Switch normal, signals east.
3-----	+	-	+	Switch normal, signals west.
4-----	+	-	-	Not used.
5-----	-	+	+	Switch reverse, signals stop.
6-----	-	+	-	Switch reverse, signals east.
7-----	-	-	+	Switch reverse, signals west.
8-----	-	-	-	Not used.

More specifically there is a group of control levers in the control office for each field station. The positioning of the levers for a particular station, followed by the actuation of suitable means to initiate the system, causes the transmission of a series of impulses comprising the code call for that station and the control code for operating the switch and controlling the signals at the selected station.

Following the transmission of the station code call, the control code is impressed upon the control line circuit as determined in accordance with the positions of the control levers for the particular station. In the examples chosen it is assumed that there is a signal control lever and a switch control lever, thus requiring three successive impulses to make the required combinations, as illustrated in the above table. It will be understood that the headings in this table, first step, second step, and third step refer to the first, second and third steps (3V, 4V and 5V) after station selection.

It is assumed that these codes are transmitted when the control levers are in their proper positions to give the desired controlling conditions at the field station as assigned to each code combination in the table. For example, if the switch lever is in a normal position and the signal lever is in an east clearing position, the second code will be transmitted consisting of (+) (+) (—). This code is effective to position the track switch TS in a normal position and to clear east bound signal 1A.

Station selection and step-by-step operation.—At the beginning of a cycle of operations relay FP is energized by polar contact 11 of relay F in either a right or a left hand position, depending upon the polarity with which line relay F is energized. The closure of front contact 13 of relay FP energizes slow acting relay SA, which picks up after a short interval of time, remains picked up throughout the cycle and drops after the expiration of an interval of time after the control line has been de-energized at the end of the cycle.

Upon the first de-energization of the control line, as repeated by relay FP following its first energization (relay SA being picked up), the first stepping relay is picked up and similarly during 5 each following de-energized condition of the control line circuit a succeeding stepping relay is picked up, so that after the station has been selected by the energization of relay ST, the control steps are then taken by stepping relays 3V, 10 4V and 5V. After the station is selected by the picking up of relay ST, the succeeding impulses in the control line circuit are effective to energize the control buses by way of contact 17 of relay F, as determined by the polarity of the impulses received from the line circuit. These buses have been given reference characters 1+, 2+, 1-, 2-, 15 3+, 3- to indicate that they are energized with the polarity indicated at the step indicated by the preceding numeral.

20 *Normal conditions.*—As previously mentioned the detector track section associated with the track switch is of the normally closed track circuit type, so that the track relay T is normally energized as is readily understood. With the 25 front contact 31 of relay T closed, an obvious energizing circuit for its repeating relay TP is closed. It will also be understood that the red or stop indicators of the signals 1A—1B and 2A—2B are energized under normal conditions, 30 since all signals normally indicate stop.

It will be assumed that the last previous operation of the system was the reception of a stop code, so that all of the other relays shown on the drawing are in their normal conditions.

35 *Reception of control impulses.*—If the character of the first impulse is positive, then the normal switch machine control relay WN is energized, while if the character of the first impulse is negative the reverse switch machine control relay WR 40 is energized. At the first step of the cycle circuits are closed for energizing both signal relays RD and LD, then if the character of the second impulse is positive relay LD will be de-energized and relay RD will remain energized. If the 45 character of the second impulse is negative relay RD will be de-energized and relay LD will remain energized. If the character of the third impulse is positive relay RD will be de-energized and if the character of the third impulse is negative 50 relay LD will be de-energized.

More specifically, as soon as the station is selected relay ST is energized and closes a circuit for picking up relay STS extending from (+), front contact 29 of relay ST, back contact 21 of 55 relay WR, back contact 22 of relay WN and winding of relay STS to (-). Relay STS closes a stick circuit for itself extending from (+), front contact 20 of relay ST, front contact 23 and winding of relay STS to (-). Relay ST, at its 60 front contact 16, connects (+) to contact 17 of relay F, so that the following impulses will be effective to energize the code conductors in the various combinations presently to be explained.

With relay STS picked up a circuit is closed for 65 picking up relay RD (when the third step is taken) which extends from (+), back contact 24 of relay 4V, front contact 25 of relay 3V, front contact 26 of relay STS and upper winding of relay RD to (-). A circuit is closed for picking 70 up relay LD which extends from (+), back contact 27 of relay 4V, front contact 28 of relay 3V, front contact 29 of relay STS and upper winding of relay LD to (-). Relays RD and LD close stick circuits for themselves including their front 75 contacts 35 and 36 to (+) at front contact 37 of

relay T. It will be noted that the picking up of both relays RD and LD is ineffective to close any signal clearing circuits because back contact 38 of relay LD is open and back contact 39 of relay RD is open.

5 *Code No. 1.*—The (+) impulse received on the first step positions relay F to the right for closing a circuit for picking up relay WN extending from (+), front contact 16 of relay ST, contact 17 of relay F in its right hand dotted position, 10 back contacts 18 and 19 of relays 5V and 4V respectively, front contact 30 of relay 3V, 1+ bus, front contact 40 of relay STS and winding of relay WN to (-). Relay WN closes a stick circuit for itself extending from (+), front contact 41 of relay STS, front contact 42 and winding of relay WN to (-). It will be understood that relay STS is de-energized at the end of the cycle when relay ST opens its front contact 20 to de-energize the stick circuit of relay STS.

20 The (+) impulse received on the second step closes a circuit for de-energizing relay LD which extends from (+), front contact 16 of relay ST, contact 17 of relay F in its right hand dotted position, back contact 18 of relay 5V, front contact 19 of relay 4V, 2+ bus, front contact 46 of relay STS, front contact 47 and lower winding of relay LD to (-). Since relay LD has its upper winding energized in the direction indicated by the arrow associated with this winding and since the last traced circuit energizes its lower winding in the direction of the arrow associated with this winding, the relay will be de-energized because of the neutralizing effects of these two windings on the armature.

35 The reception of impulse 3+ closes a circuit for de-energizing relay RD in a manner similar to that explained in connection with relay LD, which circuit extends from (+), front contact 16 of relay ST, contact 17 of relay F in its right 40 hand dotted position, front contact 18 of relay 5V, 3+ bus, front contact 48 of relay STS, front contact 49 and lower winding of relay RD to (-).

With relays RD and LD de-energized there is no circuit closed for clearing any of the signals, 45 because front contacts 38 and 50 of relays LD and RD respectively are open. Since relay ST drops before relay STS, the stick circuit of relay WN is maintained energized at back contact 20 of relay ST so that relay WN remains picked up. The switch machine is now operated to its normal position over a circuit extending from (+), front contact 43 of relay WN, back contact 44 of relay STS, normal operating wire N, switch machine motor, reverse operating wire R and 55 back contact 45 of relay WR to (-). The above described code is one that is conveniently used when all signals are at stop, for operating the switch machine to normal without clearing a signal. This is of advantage in clearing the 60 switch of obstructions due to ice and the like.

65 *Code No. 2.*—The number 1+ impulse of this code is effective to pick up relay WN and this relay is stuck up in the manner previously described. The number 2+ impulse is effective to 65 kick down relay LD as above pointed out. The number 3- impulse is ineffective, since the circuit of this code bus extends through front contact 50 of relay STS to the same contact (47) on relay LD as used by the 2+ impulse for de-energizing this relay. Therefore impulse 3- is ineffective with the result that the end of the 70 cycle is reached with relays WN and RD energized. The dropping of relay STS closes its back contact 44 for operating the switch machine 75

to its normal position by way of front contact 43 of relay WN. A circuit is now closed for clearing signal 1A which extends from (+), back contact 38 of relay LD, front contact 58 of relay 5 RD, back contact 59 of relay WR, front contact 57 of relay WN and normal east conductor NE to signal 1A.

Code No. 3.—The 1+ impulse is effective as before to operate the switch machine to its normal position when relay STS drops at the end of the cycle with relay WN picked up. The 2 impulse closes a circuit for de-energizing relay RD which extends from (+), front contact 16 of relay ST, contact 17 of relay F in its left hand dotted position, back contact 32 of relay 5V, front contact 33 of relay 4V, 2— bus, front contact 51 of relay STS, front contact 49 and lower winding of relay RD to (—). Relay RD is kicked down by this circuit. The 3+ impulse is ineffective since front contact 49 of relay RD is now open. Signal 2A is cleared over a circuit extending from (+), front contact 38 of relay LD, back contact 39 of relay RD, back contact 52 of relay WR, front contact 53 of relay WN and normal west conductor NW to signal 2A.

Code No. 4.—This code is not used but it will be later explained what happens in the event that this code is inadvertently received, due to the reception of a wrong impulse in connection with one of the other code combinations.

Code No. 5.—The number 1— impulse closes a circuit for picking up relay WR extending from (+), front contact 16 of relay ST, contact 17 of relay F in its left hand dotted position, back contacts 32 and 33 of relays 5V and 4V respectively, front contact 34 of relay 3V, 1— bus, front contact 54 of relay STS and winding of relay WR to (—). Relay WR closes a stick circuit for itself extending from (+), front contact 41 of relay STS, front contact 55 and winding of relay WR to (—). This stick circuit is maintained energized after the completion of this cycle of operations at back contact 20 of relay ST. At the end of the cycle a circuit is closed for operating the switch machine to its reverse position extending from (+), front contact 45 of relay WR, reverse conductor R, switch machine motor, normal conductor N, back contact 44 of relay STS and back contact 43 of relay WN to (—). Since this is a stop code used when it is desired to operate the switch machine to its reverse position without clearing any of the signals, the 2+ and 3+ impulses are effective to kick down relays LD and RD as before.

Code No. 6.—The number 1— impulse is effective to operate the switch machine to its reverse position as just described. The 2+ and 3— impulses are effective to kick down relay LD and to leave relay RD energized as described in connection with Code Number 2. With relay WR up, relay WN down, relay RD up and relay LD down, a circuit is closed for clearing signal 1B which extends from (+), back contact 38 of relay LD, front contact 58 of relay RD, front contact 59 of relay WR, back contact 56 of relay WN and reverse east conductor RE to signal 1B.

Code No. 7.—The number 1— impulse is effective as before for operating the switch machine to reverse. The No. 2— and 3+ impulses are effective as in Code No. 3 to kick down relay RD and leave relay LD energized. A circuit is closed for clearing signal 2B which extends from (+), front contact 38 of relay LD, back contact 39 of relay RD, front contact 52 of relay WR, back

contact 60 of relay WN and reverse west conductor RW to signal 2B.

Code No. 8.—This code combination is not used in the present embodiment, but the combination of impulses in this code which may be received due to the reception of a wrong code is effective to produce certain results which will be later described.

When any of the signals are cleared, the occupancy of the track section results in relay T being de-energized to drop its front contact 37. This de-energizes the stick circuits of the RD and LD relays, so that the energized one of these relays will be de-energized to put all signals to stop, by opening front contacts 38 and 58 of these relays. Shortly after relay T drops its contacts, relay TP is de-energized to close its back contact 61 which again energizes the stick conductor of the direction relays. Therefore a code may be transmitted, received and stored while the track section is occupied. It will be understood that this code is not effective to clear a signal while the train is in the track section, because of certain correspondence and lock circuits which are provided and which are familiar to those skilled in the art. Therefore these additional circuits need not be explained in connection with the present disclosure.

For convenience in describing how a route may be put to stop, it will be assumed that the track switch TS is in a reverse position and the signal 2B has been cleared as previously described. This route may be put to stop by the passage of a train over the detector track section as previously described, or by manual manipulation of the control lever in the control office. It will now be explained how this stop code (either (+) (+) (+) or (—) (+) (+)) is received and how it puts the cleared route to stop.

Since a stop control code need be received only when a route is actually cleared, the reception of the stop code can be made dependent upon the prior reception of a proceed code. Since it is assumed that the switch is in a reverse position with signal 2B cleared the previous proceed code was (—) (—) (+), resulting in control relays WR and LD being up.

Since relay WR is up and its back contact 21 open, relay STS cannot be picked up at the start of this cycle. Therefore, the first impulse either (+) or (—) is not effective to energize either of the switch control relays, because the 1+ and the 1— buses are open at front contacts 40 and 54 respectively of relay STS. The number 2+ impulse is effective to pick up stop relay 1S over a circuit extending from (+), front contact 16 of relay ST, contact 17 of relay F in its right hand dotted position, back contact 18 of relay 5V, front contact 19 of relay 4V, 2+ bus, back contact 46 of relay STS, back contact 62 of relay 2S and upper winding of relay 1S to (—). Relay 1S closes a stick circuit for itself extending from (+), front contact 63 of relay ST, front contact 64 and upper winding of relay 1S to (—). The 3+ impulse closes a circuit for picking up relay 2S extending from (+), front contact 16 of relay ST, contact 17 of relay F in its right hand dotted position, front contact 18 of relay 5V, 3+ bus, back contact 48 of relay STS and winding of relay 2S to (—). Relay 2S closes an obvious stick circuit for itself at its front contact 65.

At the end of the cycle, relay SA closes its back contact 66 before relay LV opens its front contact 67, so that a momentary impulse is extended through these two contacts and through front 75

contact 68 of relay 2S, front contact 69 of relay 1S, front contact 70 and lower winding of relay LD to (—). This momentary impulse kicks down relay LD and since relay RD is already down all signals are put to stop. With both front contacts 71 and 72 of relays RD and LD, respectively, down and with front contact 41 of relay STS down, the stick circuit for relays WN and WR is de-energized before relay ST drops its contact 20 at the end of the cycle. This results in de-energizing relay WR so that all of the control relays WN, WR, RD, and LD are restored to normal. Relays 1S and 2S are de-energized when relay ST drops its front contact 63 at the 15 end of the cycle.

It will be evident that the stop code is effective to pick up the 1S and 2S relays during a cycle, at the beginning of which relay STS could not be picked up because some signal was cleared. It

20 is believed that the above example is sufficient to indicate that this stop code is effective with either of the switch control relays or either of the direction relays picked up. In the event that relay RD is picked up to clear an east bound signal, then 25 the reception of a stop code is effective to kick down relay RD by means of the previously described circuit now extending through front contacts 168 and 169 of the stop relays, front contact 73 and lower winding of relay RD to (—).

30 With reference to the above code table it is apparent that the track switch can be operated to normal or reverse positions at the will of the operator, without clearing a route by the use of Codes 1 and 5 respectively. The use of such codes 35 to effect the operation of the track switch must be transmitted after the signals have been put to stop, because the switch control relays can not be changed in their positions while a signal is clear. This is due to the fact that either direction relay 40 maintains the stick circuit for the switch control relays energized and this condition prevents the picking up of relay STS at the beginning of a cycle, so that it is necessary to transmit a stop code for restoring these control relays to normal 45 before the track switch can be operated without clearing a signal.

Reception of wrong codes.—An important feature of the present invention relates to the arrangement of the codes and the circuits controlled by these codes for preventing the faulty operation 50 of the track switch, the clearing of a wrong signal or the putting of signals to stop upon the reception of an improper code. The following explanation will be devoted to the code combinations which 55 are used for operating the switch machine and clearing the signals in various combinations, as given in the above code table.

Code No. 1.—It will first be assumed that some signal is clear when this code is received. Since 60 relay STS cannot be picked up the only code buses effective are 2+, 2—, 3+ and 3—. Therefore a 1+ or a 1— impulse is ineffective to change anything. If the second impulse is (+) and (—) received in this order, the 2+ impulse will pick up 65 relay 1S and the 2— impulse will immediately kick it down. The circuit for kicking down relay 1S extends from (+), front contact 16 of relay ST, contact 17 of relay F in its left hand dotted position, back contact 32 of relay 5V, front contact 33 70 of relay 4V, 2— bus, back contact 51 of relay STS, front contact 74 and lower winding of relay 1S to (—). If the 2— impulse is received first, relay 2S will be picked up over a circuit extending through back contact 74 of relay 1S. Then the 2+ impulse 75 will be ineffective because back contact 62 of

relay 2S is open. If the third impulse is 3+ relay 2S will be picked up, if not already up, but in any event relay 1S is down. If the third impulse is 3— this impulse is ineffective because relay 1S is down and its front contact 75 is open. With front contacts 69 and 169 of relay 1S open the stop code is ineffective to put signals to stop.

If 2+ only is received on the second step relay 1S will be picked up then if a 3— is received on the third step, either alone or with a 3+, relay 1S will be kicked down. Since both stop relays must be up to render the stop code effective it will be seen that a reception of a wrong code, an extra impulse or the omission of an impulse will prevent the cleared signals being put to stop by preventing both stop relays being up when relay SA drops its contact 66 at the end of the cycle.

It will now be assumed that all signals are at stop at the beginning of a cycle during which 20 Code No. 1 is received. This means that relay STS will be picked up at the start of the cycle. If a (+) and a (—) impulse are received on the first step, both the 1+ and the 1— buses will be energized to pick up relays WN and WR. With both contacts 43 and 45 of these relays picked up the switch machine motor cannot be energized and since contact 44 of relay STS is picked up at the time that the number 1 impulse is received it makes no difference which relay WN or WR is 30 picked up first.

With both relays WN and WR picked up no signal can be cleared, because the signal clearing circuits require that one or the other of these relays be down. If the second impulse received is both (+) and (—), both the 2+ and 2— buses are 35 energized which results in kicking down relays LD and RD so that no signal will be cleared. Upon the reception of a (+) and a (—) impulse at the third step, both buses 3+ and 3— will be energized for kicking down relays RD and LD so 40 that no signal can be cleared. It will thus be seen that under this condition the reception of an extra impulse in connection with a stop code is ineffective to falsely clear a signal.

Code No. 2.—The reception of a surge at the 45 first step which energizes buses 1+ and 1— will pick up relays WN and WR so that no signal can be cleared and the switch machine position cannot be changed, for the reasons described in connection with Code No. 1. The reception of (+) and (—) impulses at the second step kicks down both direction relays so that no signal can be cleared. The reception of (+) and (—) impulses at the third step kicks down both direction relays so that no signal can be cleared.

Code No. 3.—The reception of two impulses at the first step in connection with this code effects the same operation as described in connection with Code No. 1. The reception of (+) and (—) impulses at the second step kicks down both direction relays, because the energization of buses 2+ and 2— energize the lower windings of these two relays in opposition to their upper windings as previously described. Similarly the reception of (+) and (—) impulses at the third step kick down 60 these direction relays in the previously described manner.

It is believed unnecessary to describe the detailed operation of the result due to the reception of surges in connection with the other three codes, 70 since the surges affect the control relays in the same manner already described. In the event that an impulse is not received for a sufficient time to energize the control buses for picking up the switch control relays, or for kicking down the 75

direction relays the result is that no wrong condition will be effected. This is because with both relays WN and WR down the switch machine cannot be operated and a signal cannot be cleared 5 and with both relays RD and LD up no signal can be cleared.

In connection with the signal clearing codes, the reception of a wrong code at any one step is ineffective to clear a signal but the control circuits will be left in the conditions last assumed. For example, in connection with Code No. 2, if the second impulse is received (—) instead of (+) in Code No. 2 and the third impulse is properly received (—), energizing the 2— bus 10 on the second step kicks down relay RD and energizing the 3— bus on the third step kicks down relay LD so that no signal will be cleared.

If the second impulse is properly received (+) relay LD will be kicked down, then if the third 20 impulse is improperly received (+), relay RD will be kicked down and no signal will be cleared.

It is believed that the above examples are sufficient to indicate how the present invention is arranged for checking against extra impulses received, due to surges or the like, against wrong impulses received and against the absence of impulses at the different steps of the cycle.

The system contemplated by the present invention is arranged so that correspondence is required between the track switch and the switch control relays, so that a route cannot be cleared without the proper response of the switch machine. Since this portion of the system is immaterial to an understanding of the features of 35 the present invention it has been omitted from the present disclosure for the sake of simplicity. Such correspondence circuits may be as disclosed in the prior application of T. J. Judge, Ser. No. 678,045, filed June 28, 1933.

40 These various features and others which are apparent from a study of the above description, provides a safe and reliable control for the traffic controlling devices through the medium of a code type communication system.

45 Having thus described a centralized traffic controlling system as one embodiment of the present invention, it is desired to be understood that this form is selected to facilitate in the disclosure of the invention rather than to limit the number of 50 forms which it may assume and it is to be further understood that various modifications, adaptations and alterations may be applied to the specific form shown to meet the requirements of practice, without in any manner departing from 55 the spirit or scope of the present invention, except as limited by the appended claims.

What I claim is:—

1. In combination, a track switch, signals for governing traffic over said track switch, clearing circuits for said signals, a line circuit having a series of coded impulses successively transmitted thereover, means for storing an initial code of said series and concomitantly therewith effecting selection of one of said clearing circuits, means 60 responsive to a second code of said series for energizing said selected clearing circuit, and means responsive to a third code of said series for confirming said selection.

2. In combination, a track switch, signals for governing traffic over said track switch, clearing circuits for said signals, a line circuit having a series of coded impulses successively transmitted thereover, means for storing an initial code of said series and concomitantly therewith effecting selection of one of said clearing circuits, and 70

means responsive to a subsequent code of said series for cancelling said selection.

3. In combination, a track switch, signals for governing traffic over said track switch, clearing circuits for said signals, a line circuit having a series of characteristic impulses successively transmitted thereover, means for receiving said impulses, means responsive to the reception of an impulse of said series for preparing one of said clearing circuits, means responsive to the 10 reception of succeeding impulses of said series of unlike character for completing said prepared circuit, and means responsive to the reception of succeeding impulses of said series of like character for annulling said prepared circuit. 15

4. In combination, a track switch, signals for governing traffic over said track switch, a clearing circuit for each of said signals, a line circuit having a series of impulses transmitted thereover, means for registering said impulses, means responsive to a first one of said impulses for controlling said track switch and for selecting a plurality of said clearing circuits, means responsive to a second one of said impulses for selecting and energizing one of said plurality of clearing circuits, and means responsive to a third one of said impulses for immediately deenergizing said energized clearing circuit. 20

5. In combination, a track switch, signals for governing traffic over said track switch, a clearing circuit for each of said signals, a line circuit having a series of impulses of predetermined character transmitted thereover, means for selectively registering the character of said impulses, means responsive to a first one of said impulses for controlling said track switch and for selecting a plurality of said clearing circuits, means responsive to a second one of said impulses for selecting and energizing one of said plurality of clearing circuits, and means responsive to a third one of 30 said impulses for immediately deenergizing said energized clearing circuit. 35

6. In combination, a track switch, signals for governing traffic over said track switch, a clearing circuit for each of said signals, a line circuit having a series of impulses of predetermined character transmitted thereover, means for selectively registering the character of said impulses, means responsive to a first one of said impulses for controlling said track switch and for selecting a plurality of said clearing circuits, means responsive to a second one of said impulses for selecting and energizing one of said plurality of clearing circuits, means responsive to a third one of said impulses of one character for immediately deenergizing said energized clearing circuit, and means responsive to a third one of said impulses of another character for preventing the deenergization of said energized clearing circuit. 45

7. In combination, a line circuit having a series of positive and negative impulses forming a code transmitted thereover, a polar relay included in said line circuit, step-by-step mechanism operable to take one step for each of said impulses, 50 a pair of control relays, energizing circuits for said pair of control relays closed at one step of said mechanism, and deenergizing circuits for said pair of control relays selected by said polar relay and closed on another step of said mechanism. 65

8. In combination, a line circuit having a series of positive and negative impulses forming a code transmitted thereover, a polar relay included in said line circuit, step-by-step mechanism oper- 70

able to take one step for each of said impulses, a pair of control relays, energizing circuits for said pair of control relays closed at one step of said mechanism, and differential deenergizing circuits 5 for said pair of control relays selected by said polar relay and closed on another step of said mechanism.

9. In combination, a line circuit having a series of impulses of distinctive character transmitted 10 thereover, step-by-step mechanism operable to take one step for each of said impulses, a pair of control relays selectable at a particular step of said mechanism and energized at a previous 15 step of said mechanism, means responsive to the character of an impulse of one character received at said particular step for selectively de- 20 energizing one of said control relays, and means responsive to the reception of an impulse of another character at said particular step for de- energizing the other of said relays.

10. In a centralized traffic controlling system, a track switch, a switch machine for operating said track switch, signals for governing traffic over said track switch, a line circuit having series 25 of characteristic impulses transmitted thereover to form distinctive signal clearing and stop code combinations, means for receiving said impulses, step-by-step mechanism operable through a cycle one step for each impulse of a series, switch 30 machine control means responsive to a switch code received during a cycle, signal clearing means responsive to a signal code received during a cycle, stop control means responsive to a stop code received during a cycle, a selecting 35 relay, means controlled by said selecting relay for rendering said switch control and said signal clearing means operable by said mechanism only when said switch control and said signal clearing means are inactive at the start of a cycle, and 40 means for rendering said switch control and said signal clearing means inactive in response to a stop code when and only when some part of said switch control means or said signal clearing means is active at the start of a cycle.

45 11. In a centralized traffic controlling system, a track switch, a switch machine for operating said track switch, signals for governing traffic over said track switch, a line circuit having series 50 of characteristic impulses transmitted thereover to form distinctive signal clearing and stop code combinations, means for receiving said impulses, step-by-step mechanism operable through a cycle one step for each impulse of a series, switch 55 machine control means responsive to a switch code received during a cycle, signal clearing means responsive to a signal code received during a cycle, stop control means responsive to a stop code received during a cycle, a selecting relay, means controlled by said selecting relay for rendering said switch control and said signal clearing means operable by said mechanism only when said switch control and said signal clearing means are inactive at the start of a cycle, means 60 for rendering said switch control and said signal clearing means inactive in response to a stop code when and only when some part of said switch control means or said clearing means is active at the start of a cycle, and means controlled by said relay for preventing the operation 65 of said switch machine during a cycle at the start of which said switch control and said signal clearing means are inactive.

70 12. In combination, a switch machine for operating a railroad track switch, a line circuit 75 having a plurality of positive and negative im-

pulses applied thereto to form a distinctive code combination, a step-by-step means operable to take one step for each of said impulses, code receiving relays selectively operated at a step of said step-by-step means for controlling said switch machine, a station relay rendered active when said impulses are to control said code receiving relays, a station repeating relay rendered active only when said station relay is rendered active and all of said code receiving relays 10 are inactive, means for allowing said code receiving relays to be controlled in accordance with said code combination only when said station repeating relay is rendered active, and means for allowing said switch machine to be controlled 15 by said code receiving relays only when said station repeating relay is rendered inactive.

13. In combination, a railroad track section, a track switch associated with said section, signals for governing traffic over said track switch, 20 clearing circuits for said signals, a line circuit having a series of characteristic impulses successively transmitted thereover, means for receiving said impulses, means responsive to the reception of an impulse of said series for preparing one of said clearing circuits, means responsive to the reception of succeeding impulses of said series of unlike character for completing said prepared circuit, means responsive to the reception of succeeding impulses of said series of 25 like character for annulling said prepared circuit, and means controlled by the occupancy of said section for annulling said prepared circuit.

14. In combination, a line circuit having a series 30 of positive and negative impulses forming a code transmitted thereover, a polar relay included in said line circuit, step-by-step mechanism operable to take one step for each of said impulses, a pair 35 of control relays, energizing circuits for said pair of control relays closed at one step of said mechanism, stick circuits for said pair of control relays, deenergizing circuits for said pair of control relays independent of said stick circuits selected by said polar relay and closed on another step of said mechanism, and means for deenergizing said pair of control relays by the deenergization of said stick circuits.

15. In combination, a line circuit having a series 40 of impulses of distinctive character transmitted thereover, step-by-step mechanism operable to take one step for each of said impulses, a pair of control relays selectable at a particular step of said mechanism and energized at a previous step of said mechanism, a track section 45 including a track switch governed by said control relays, means responsive to the character of an impulse of one character received at said particular step for selectively deenergizing one of said control relays, means responsive to the reception 50 of an impulse of another character at said particular step for deenergizing the other of said relays, and means controlled by the occupancy of said section for deenergizing both of said relays.

16. In combination, two control relays each 55 having active and inactive positions, conditioning means for simultaneously operating said control relays, a normally energized stick circuit for said control relays, a first control means for selectively and individually releasing said control relays, a second control means independent of said stick circuit for simultaneously releasing said control relays, a third control means for releasing said control relays by deenergizing said stick circuit, and a plurality of channel circuits selectively 60

energized in accordance with the positions of said control relays.

17. In combination, a line circuit over which combinations of impulses comprising signal clearing and stop codes are transmitted, a code receiver connected to said line circuit for receiving said codes, a railroad track switch and a plurality of signals associated with said code receiver, a plurality of signal control relays for controlling said signals, means for energizing said control relays at the start of a code transmitted over said line circuit, means responsive to a signal clearing code for selectively de-energizing one of said relays whereby said signals are selectively cleared, and means responsive to a stop code for de-energizing said plurality of control relays whereby said signals are put to stop.

18. In combination, a line circuit over which combinations of impulses comprising signal clearing and stop codes are transmitted, a code receiver connected to said line circuit for receiving said codes, a railroad track switch and a plurality of signals associated with said code receiver, a plurality of signal control relays for controlling said signals, means for energizing said control relays at the start of a code transmitted over said line circuit, means responsive to a signal clearing code for selectively de-energizing one of said relays whereby said signals are selectively cleared, a stop relay, means responsive to a stop code for energizing said stop relay, and means effective at the termination of said stop code and including said stop relay for de-energizing said control relays whereby said signals are put to stop.

19. In combination, a line circuit over which combinations of impulses comprising signal clearing and stop codes are transmitted, a code receiver connected to said line circuit for receiving said codes, a railroad track switch and a plurality of signals associated with said code receiver, a plurality of signal control relays for controlling said signals, means for energizing said control relays at the start of a code transmitted over said line circuit, means responsive to a signal clearing code for selectively de-energizing one of said relays whereby said signals are selectively cleared, a stop relay, means responsive to a stop code for energizing said stop relay, means effective at the termination of said stop code and including said stop relay for de-energizing said control relays whereby said signals are put to stop, and means responsive to the occupancy of the track section with which said track switch is associated for de-energizing said control relays whereby said signals are put to stop.

20. In combination; a line circuit over which combinations of impulses comprising receiver selecting, signal clearing and stop codes are transmitted; a code receiver; means responsive

to a receiver selecting code for selectively associating said code receiver with said line circuit; means including said code receiver for receiving said signal clearing and stop codes; a railroad track switch and a plurality of signals associated with said code receiver; a plurality of signal control relays for controlling said signals; means for energizing said control relays at one point of a code transmitted over said line circuit; means responsive to a signal clearing code for selectively de-energizing one of said relays whereby said signals are selectively cleared; and means responsive to a stop code for de-energizing said plurality of control relays whereby said signals are put to stop.

21. In a selecting system; a transmitting station and a receiving station connected by a line circuit, said line circuit being energized with impulses of variable polarity; a plurality of differential relays at said receiving station each having two similar windings; means at said receiving station controlled over said line circuit for picking up said relays by simultaneously energizing a first winding of each relay in response to one of said impulses; and means controlled by the polarity of other impulses received over said line circuit for releasing said relays by energizing their second windings.

22. In a selecting system; a transmitting station and a receiving station connected by a line circuit, said line circuit being energized with impulses of variable polarity; a plurality of differential relays at said receiving station each having two similar windings; means at said receiving station controlled over said line circuit for picking up said relays by simultaneously energizing a first winding of each relay in response to one of said impulses; means for sticking said relays by energizing stick circuits connected to said first windings; and means controlled by the polarity of other impulses received over said line circuit for releasing said relays by energizing their second windings.

23. In a selecting system; a transmitting station and a receiving station connected by a line circuit, said line circuit being energized with impulses of variable polarity; a plurality of differential relays at said receiving station each having two similar windings; means at said receiving station controlled over said line circuit for picking up said relays by simultaneously energizing a first winding of each relay in response to one of said impulses; means for sticking said relays by energizing stick circuits connected to said first windings; and means controlled by the polarity of another of said impulses received over said line circuit for selectively releasing one of said relays by energizing its second winding.

WINFRED T. POWELL.
